INVENTOR

ROBERT H. ROMIG

Delham C. Linton
ATTORNEY

UNITED STATES PATENT OFFICE.

ROBERT H. ROMIG, OF ANCHORAGE, TERRITORY OF ALASKA.

PAPER-FASTENING DEVICE.

Application filed April 27, 1923. Serial No. 635,042.

To all whom it may concern:

Be it known that I, ROBERT H. ROMIG, a citizen of the United States of America, residing at Anchorage, Territory of Alaska, have invented certain new and useful Improvements in Paper-Fastening Devices; and I do hereby declare that the following is a full, clear, concise, and exact description of the invention, such as will enable others skilled in the art to which it appertains to make and use the same.

This invention relates to improvements in paper fastening or binding devices, having for an object to provide a novel form of spring clip particularly advantageous for use in the packaging or binding of paper currency in banking and finance institutions, whereby the paper notes will be positively and securely held in juxtaposed or packaged relation, thus preventing displacement of any one or more than one during subsequent handling, means being arranged on the clip for receiving and retaining an indicia or value indicating tag in order that the contents of the package may be readily ascertained.

It is likewise an object of the invention to provide a currency clip of the character mentioned which, because of its construction, may be used and reused for an indefinite period of time, thus avoiding waste, as where paper strips bearing value indicating notations are employed for binding or packing paper currency.

Other objects will be in part obvious and in part pointed out hereinafter.

In order that the invention and its mode of application may be readily understood by persons skilled in the art, I have in the accompanying illustrative drawings, and in the detailed following description based thereon, set out one possible embodiment of the same.

In these drawings:—

Figure 1 is a perspective view of the improved clip showing the same applied to a package of currency, the latter being shown in dotted lines;

Figure 2 is a plan view of the improved clip;

Figure 3 is a side elevation thereof;

Figure 4 is a bottom plan view of the clip; and

Figure 5 is an end elevation of the same.

Having more particular reference to the

drawings, in connection with which like characters of reference will designate corresponding parts throughout, the improved clip may be stated to comprise a single length of spring material, such as wire or the like, a portion of which is bent into an elongated looped body portion indicated by the numeral 1, the sides of such body portion being arranged in parallel relationship, whereby to permit the securing of an indicia bearing plate 2 thereto, connection between the plate and the parallel sides of the elongated looped body portion 1 being effected by flanging the opposite sides of said plate and bending the same into engagement with adjacent portions of the body as indicated by the numeral 3. In this connection, it is to be noted that the indicia bearing plate 2 is of a length such as will cover the greater portion of the body 1 and in consequence, will provide an effectual brace for the flexible parallel sides of spring material, thus preventing relative movement therebetween during usage of the clip and also, lending to the stability of the device in general.

One extremity of the looped body portion 1 is extended coincidentally with the same but at an oblique angle thereto, thus constituting a clamping or binding arm 4, the free portion of which arm is bent upon itself in substantially looped or U-shaped fashion, as indicated by the numeral 5, thus providing said arm with two substantially parallel side portions and causing the arm so constructed to be of a width corresponding or approximately corresponding to the width of the body portion 1. In this connection, it is to be noted that the free end of the binding or clamping arm 4 extends to a point slightly inwardly of one end of the indicia bearing plate 2. In consequence paper currency engaged between the arm 4 and the body portion 1 carrying the indicia bearing plate will be caused to be clamping-ly engaged with said body portion and because of the bracing-like action of the indicia bearing plate 2 with respect to the opposite sides of said body portion, flexing movement as between the opposite sides of the body portion will be prevented and in consequence, the paper notes comprising the package will be firmly secured by the device.

It is to be understood that the face or outer side of the indicia bearing plate may

be supplied with any form of notation indicating the value of the package of currency held thereby, such as indicated by the numeral 6, this notation being removable from the plate when it is desired to use the same for binding or packaging a bundle of currency of different value.

Because of the construction of the improved clip, it will be readily understood that the same may be used and reused in the packaging or binding of paper currency for an indefinite period and because of this, expensive wastage occurring with the use of paper binding strips bearing value indicating notations thereon will be eliminated. Furthermore, because of the clamping-like engagement of the arm 4 with the currency, it will be understood that any one or more of the notes secured thereby will be prevented from becoming displaced from the package and bundle and therefore, the device will be found much more practical than the now prevalent form of packaging money by passing gummed paper strips about the same and joining the adhesive coated ends thereof.

Manifestly, the construction shown is capable of considerable modification and such modification as is within the scope of my claims, I consider within the spirit of my invention.

I claim:

1. A device of the character described comprising an elongated looped body portion formed of a single length of spring material, an arm disposed coincidentally with said body portion but at an oblique angle thereto, and an indicia bearing plate

secured to the opposite sides of said body portion.

2. A device of the character described comprising an elongated looped body portion formed of a single length of spring material and having substantially parallel sides, an arm extending from one extremity of the looped body portion coincidentally therewith but arranged at an oblique angle thereto, said arm being bent upon itself into substantially U-shaped fashion and of a width approximately corresponding to the width of said body portion, and an indicia bearing plate clampingly secured to the parallel opposite sides of the body portion.

3. A device of the character described comprising an elongated looped body portion formed of a single length of spring material and having substantially parallel opposite side portions, a sheet metal indicia bearing plate clampingly engaged with said parallel opposite sides of the body portion and covering the greater portion of said body portion, one extremity of said body portion being arranged at an oblique angle thereto and extended coincidentally with the same, the free portion of said extremity being bent upon itself in substantially U-shaped fashion whereby to provide a clamping arm of a width approximately corresponding to the width of said body portion, the free end of said arm being extended to a point in proximity to one end of said indicia bearing plate.

In witness whereof I have hereunto set my hand.

ROBERT H. ROMIG.
